UNITED STATES PATENT OFFICE

2,449,567

FOUNTAIN PEN

Ludwig F. Perwas, Bronx, N. Y.

Application April 4, 1946, Serial No. 659,591

6 Claims. (Cl. 120—47)

1

This invention relates to improvements in fountain pens of the type having conical-shaped points with ink pumping filling instrumentalities therein, and in particular a resiliently held point with the point forming a valve and with a vent extending through a tubular piston rod of the pumping mechanism and wherein the vent is provided with closing means at the inner and outer ends thereof.

The object of this invention is to provide a point for fountain pens that is only open to permit flow of ink when the point is pressed against a writing surface, and in which improved pumping mechanism is provided for filling.

Another object of the invention is to provide a pen having an improved leak proof mechanism.

Another object of the invention is to provide a pen having a leakproof valve ring that will prevent leakage of the pen regardless of the altitude to which it is subjected.

Another object of the invention is to provide a pen which will insure a full supply of ink at the time it is filled.

With the above and other objects and advantages in view the invention consists of the novel details of construction, arrangement and combination of parts more fully hereinafter described, claimed and illustrated in the accompanying drawings in which:

Figure 1 is a vertical sectional view of an embodiment of the invention;

Figure 2 is a cross sectional view on the line 2—2 of Figure 1;

Figure 3 is the same on the line 3—3 of Figure 1;

Figure 4 is the same on the line 4—4 of Figure 1;

Figure 5 is the same on the line 5—5 of Figure 1;

Figure 6 is the same on the line 6—6 of Figure 1;

Figure 7 is a detailed fragmentary view of a modified form of pumping mechanism;

Figure 8 is a cross sectional view on the line 8—8 of Figure 7;

Figure 9 is the same on the line 9—9 of Figure 7;

Figure 10 is another modified form of pumping mechanism;

Figure 11 is a cross sectional view on the line 11—11 of Figure 10;

Figure 12 is the same on the line 12—12 of Figure 10;

Figure 13 is a modified form of a pen point

2

and ink feeding means taken on line 13—13 of Figure 15;

Figure 14 is a cross sectional view on the line 14—14 of Figure 13;

Figure 15 is the same on the line 15—15 of Figure 13;

Figure 16 is a plan view of the valve ring;

Figure 17 is a side view thereof;

Figure 18 is a detailed view of the control valve shown in Figure 1;

Figure 19 is a sectional view of the pen point, and

Figure 20 is a sectional view on the line 20—20 of Figure 18;

Referring more in detail to the drawings and in particular to Figures 1 to 6 inclusive, the reference numeral 30 designates the tubular housing or casing on which at the top thereof is provided the removable cover 32. The housing 30 at the upper end thereof is internally threaded to receive the threaded plug 34 in which is threadedly mounted the tapered end 36 at the upper end of which is threadedly mounted the tapered point housing 38 having the tapered pen point 40 loosely fitted therein.

The pen point 40 is provided with vertical ink feed grooves 42 which may consist of one or more as desired.

Threadedly mounted in the housing 38 is the adjusting member 44 having a seat 46 therein to receive one end of a spring 48 the other end of which engages the point 40 and adjustment of the member 44 tensions the spring 48 for the adjustment of pressure on the point 40.

The end 36 is provided with a passageway 50 which at the upper end communicates with the port 52 in the housing 38 and at the lower end with the circular groove 54 in the housing 36 which communicates with the circular groove 56 in the plug 34.

Mounted in the communicating grooves 54 and 56 is a circular ring 58 made of plastic or other buoyant resilient material. Communicating with groove 56 in the plug 34 are the vertical passageways 60 which at their lower ends communicate with the circular seat 62.

An inclined air outlet passageway 64 is provided in the end 36 which communicates with the air escape tube 66 in the housing 30 and a spring pressed ball valve 68 is provided in the seat 60 at their point of communication and the valve 68 seats in the upper end of the tube 66.

The plug 34 is provided with a circular recess 72 in which a circular band spring 74 is positioned which urges detents 76 outwardly of the

housing 30 to frictionally contact the inner surface of the cover to retain the cover 32 on the housing 30.

A compression spring 78 mounted on the tube 66 has one end engageable in the seat 62 and the other end engaging the piston 80.

The piston 80 is provided with a rib 82 or if desired more ribs may be provided to strengthen the mechanism, the ribs also function as alignment means for positioning the piston and plug in relation to each other. A valve 84 is provided in the piston 80 to permit air to escape from the housing 30.

Mounted on the lower end of the tube 66 is the tubular control rod 86 having a circular plate 88 formed integral therewith and a resilient gasket 90 secured to the plate 88 engages the lower surface of the piston 80 and the upper end of the rod 86 enters the bore 92 in the piston 80 and the rod 86 is provided with air ports 94.

The lower end of the tube 66 is closed by the plug valve 96 mounted in the guide fingers 98 in the rod 86 and the valve 96 is forced into closing position by the spring 100 engaging the valve at one end and the cap 102 at the other end.

A threaded plug 104 is mounted in the end of the housing 30 and is provided with a bore 106 in which the rod 86 is mounted.

A circular recess 108 communicating with the bore 106 has a circular or oval packing ring 110 mounted therein, which is retained in position by the double flange compression ring or collar 112 which is engaged by the threaded adjusting screw 114 and the collar 112 engages the ribs 116 of the bottom cover 118 which is threadedly mounted on the plug 104.

The cover 32 is provided with a pocket clip 120 that is retained thereon by a plug 122 having a central seat 124 in which is mounted the stud 126 which is threadedly mounted in the resilient air-tight cover 128 within the cover 32 and cover 128 engages the tapered end 36. A locknut 130 retains the stud 126 which engages at the upper end thereof the nut 130, and at the lower end the tip 136 formed on the end of the cover 128.

In Figure 3 the piston 80 is shown with arcuate shaped slots 138 to permit the liquid to rise beyond the piston 80 thereby increasing the liquid supply capacity by utilizing all available space.

In Figure 4 the plate 88 is shown with the arcuate shaped control slot 140 which will coincide with slot 138 upon adjustment thereof.

In Figures 7 to 9 inclusive, the housing 30a is provided with the partition 142 adjacent the lower end thereof to support the rod 86a and a seat 144 therein receives the packing ring 110 which is retained therein by the washer 146 and adjusting screw 148 and the ribs 116 have been eliminated from the cover 118a which as shown is threadedly connected to the housing 30a.

Formed integral with the upper end of the rod 86a is the piston 150 having the piston ring 152 mounted therein and provided with vertical openings 154 for air and liquid supply. A circular seat 156 communicates with the openings 154 and has a resilient buoyant circular valve 158 of plastic or other material mounted therein which prevents escape of the liquid supply due to changes in atmospheric conditions. A collar 160 mounted on the rod 86a engages the lower ends of the seat 156 and retains valve 158 in the seat.

In Figure 8 the piston 150 is shown provided with arcuate shaped slots 162 for air and liquid supply.

In Figure 9 the piston 150 is shown provided

with arcuate shaped slots 164 which are similar in operation to slots 162.

In Figures 10 to 12 inclusive the housing 30b is shown having the piston 214 mounted therein and connected by a screw 216 to the manipulating tubular rod 218. This rod is positioned in the supply chamber 220 and has a passageway 222 therein which is sufficiently narrow to permit liquid to pass therein when chamber 220 is full. Piston 214 is provided with a seat 224 for the plastic resilient buoyant piston ring 226.

The ring 226 is retained in a favorable operating position by means of the circular plate 228 formed on the rod 218 and the plate 228 is provided with air and liquid passage slots 230. A spring pressed ball valve 232 closes the lower end of the passageway 222, and the spring 234 is seated adjacent the knob 236 which is threadedly connected to the rod 218. A partition 238 supports the rod 218 and the under side engages the resilient packing ring 240 which is retained in place by the packing ring 242 and adjusting screw 244. Positioned in the rod 218 adjacent the valve 232 is the transverse air escape opening 244 and a compression spring 246 engages the piston 214 on the top thereof and a bottom cover 248 is threadedly connected to the housing 30b at the lower end thereof.

In Figure 11 the piston 214 is shown with the arcuate shaped slots 250 and in Figure 12 with the arcuate shaped air and liquid slots 252.

In Figures 10 to 12 inclusive the bottom cover 248 is removed and the pen point 42 is dipped into the liquid supply and the rod 218 is manipulated inwardly and outwardly several times for the filling thereof. The implement is retained a little longer in the liquid supply while replacing the cover 248 to insure complete filling thereof. When the supply is completely replenished the cover is replaced and while this is being done the liquid will flow or rise beyond the piston 214 since the valve ring 226 is buoyant and on the inward stroke the valve ring 226 will favorably tend to remain adjacent to the plate 228 since it adheres to the piston wall or housing and on the outward stroke due to spring 246 will tend to remain adjacent the piston 214 forming an air tight fit between the piston 214 and the housing 30.

In Figures 13 to 15 inclusive a capillary action siphon feed tube and improved pen point is shown.

The capillary action siphon feed tube 254 is threadedly connected to the plug 256 which in turn is threadedly connected to the interior of the housing 30b and vertical grooves or passages 258 therein communicate with the vertical passage 260 formed in the tubular member 262 formed on the plug 256. Member 262 is a capillary action siphon feed tube which with tube 254 forms the complete capillary action unit.

Tube 262 will extend downwardly toward the bottom of the supply chamber to a position below the lowest level the liquid supply can reach and tube 254 is provided with inlet ports 255.

A plug 264 is threadedly mounted in the upper end of the housing 30 and is provided with vertical openings 266 communicating with the ink reservoir 268 in which is formed a channel 270 which is adjusted by means of the adjusting screw 272 having ports or channel 274 communicating with openings 266 and channel 270. A channel 276 communicates with passage 260 and channel 278 will communicate with ports 274 and passage 280 in end 36.

The pen point 282 has ink grooves 284 and ports 286 leading from seat 288 in which the compression spring 290 is mounted and the spring is retained in the seat by the adjusting screw 292.

The seat 288 is not tapered and this will only prevent wobbling of the point but the seat functions as an ink reservoir and when the point moves inwardly due to the pressure of contacting a writing surface ink will flow through the grooves. The ports 286 are connected to the grooves 284 by the tapered formation of the point to permit ink to flow into the grooves but when pressure is relieved the pen point will seal the supply of liquid thereto.

By capillary action the liquid passes through ports 255, grooves 258, passage 260 to reservoir 268 then to seat 288 and to the pen point. Through this arrangement pressure is avoided thereby preventing overflowing and making a full supply of ink in the pump reservoir. The capillary action feed tube coacts with the pump mechanism preventing the liquid in the pump reservoir from flowing out, due to the full supply obtained by the operation of the pump mechanism.

Figures 16 and 17 show a resilient valve or packing ring 294 which is similar in construction to ring 110, 194 and 240 in which are provided ports 296.

In Figure 18 there is shown the rod 86, tube 66, valve 96 and spring 100. In Figure 19 the seat 288 is shown tapered at its upper end at 289 and the seat moves inwardly with the point. In Figure 20 there is shown rod 86, the tapered upper end of valve 96, and the guide fingers 98.

When the cover 118 is on plug 104, plug 96 prevents liquids from entering the tube 66 and air grooves 296 permit air to pass around the plug 96, shoulders 298 formed on guide fingers 98 prevent the plug 96, from falling through when the cover is removed and interfering with the operation of the pump mechanism by blocking the air entrance channels.

To fill the pen with ink the cap 32 is removed and the cap 118 unscrewed from the plug 104. The piston is then drawn outward by the tubular control rod 86 and the plate 88, the cap 118 which is on the end of the rod 86 being gripped by the thumb and forefinger, and after the barrel is filled the piston is returned to the position shown in Figure 1, the ink passing through the valves in the piston and openings in the associated parts.

In use the cap 32 is removed and as the point 40 is pressed against a surface it backs upward into the pen, opening the grooves 42, and ink will flow through the passage 50 to the point.

It is believed that the construction and operation of the device will be apparent to those skilled in the art, and it is to be understood that changes may be made in the details of construction, arrangement and combination of parts without departing from the spirit of the invention or the scope of the appended claims.

Having thus described the invention what is claimed as new and desired to be secured by Letters Patent is:

1. In a fountain pen, the combination, which comprises, a tubular housing, plugs threaded in opposite ends of the housing, a head with a conical-shaped outer surface and having a socket in the end carried by the plug at the writing end of

the housing, a conical-shaped pen point freely positioned in the socket of the head, resilient means urging the point outward to the writing position, means adjusting the pressure of the resilient means, a piston in the housing, a valve in the piston, a tubular piston rod extending from the piston through the plug in the opposite end of the housing, a cap on the outer end of the piston rod threaded on the plug through which the rod extends, and a tubular vent extending through the piston rod and to a point at the inner end of the head, said head having an outlet passage therethrough communicating with the said tubular vent.

15 2. A fountain pen as described in claim 1 having a valve between the tubular vent and the said outlet passage through the head closing the passage to prevent leakage of ink with the pen in the writing position.

20 3. A fountain pen as described in claim 1 having a cap providing a closure for the pen point, and an auxiliary cap suspended in the former cap and positioned to close the outer end of said outlet passage through the head to prevent leakage of ink through the said outlet passage.

25 4. A fountain pen as described in claim 1 having a spring around the piston rod for urging the piston inward, a packing gland in the plug at the outer end of the piston rod, and a valve in the outer end of the piston rod for closing the vent through the piston rod with the pen in the closed position.

30 5. In a fountain pen, a tubular casing, a head having a conical-shaped inner opening mounted in one end of the casing, a point having a conical-shaped outer surface to correspond with the surface of the inner opening of the head positioned in said inner opening and having longitudinally disposed grooves in the outer surface, said grooves 35 extending from the outer end of the point to a point spaced from the inner end providing a valve surface around the inner end of the point to coact with the inner opening of the head to close said opening, means resiliently urging the said point outward to seat the valve, said head having an ink passage from the point to the interior of the casing, and filling means in the casing.

40 6. A fountain pen as described in claim 5, having means adjusting the tension of the resilient 45 means for urging the point outward.

50 LUDWIG F. PERWAS.
